UNITED STATES PATENT OFFICE

MARTIN HARDSCOG, OF OTTUMWA, IOWA.

DRILL-COUPING.

980,776.

Specification of Letters Patent. Patented Jan. 3, 1911.

Application filed May 8, 1908. Serial No. 431,606.

To all whom it may concern:

Be it known that I, MARTIN HARDSCOG, a citizen of the United States, residing at Ottumwa, in the county of Wapello and State 5 of Iowa, have invented certain new and useful Improvements in Drill-Couplings, of which the following is a specification.

This invention relates to couplings for drills operated by a medium under pressure 10 and in which the drill rod and the drill are revoluble, and the means for supplying the medium under pressure is stationary, or has a fixed relation.

The object of the present invention is to 15 construct a coupling, between the fixed connection for a medium under pressure and the revoluble drill rod and drills, which will be effective and reliable in operation, and which will not leak or vent the medium under pres-

20 sure.

The invention consists in the features of construction and combinations of parts hereinafter described and claimed.

In the drawings Figure 1 is a sectional 25 elevation, with the drill rod partly in section and partly in elevation, and broken off; Fig. 2 a cross section on line 2—2 of Fig. 1, looking in the direction of the arrow; Fig. 3 a cross section on line 3—3 of Fig. 30 1, looking in the direction of the arrow; and Fig. 4 a cross section on line 4—4 of Fig. 1, looking in the direction of the arrow.

The coupling of the present invention has a main shell or casing 1, preferably of a 35 cylindrical form in cross section. The shell or casing, at its rear end, has an interior screw thread 2, into which is entered the head of a plug 3 having an interior screw thread, which plug has a rim or flange 4, 40 the face of which abuts against the end face of the shell or casing 1, when the plug is threaded into the shell or casing, making a tight joint against leakage for a medium under pressure. The plug has a neck 5 45 rearwardly extending from the center and terminating in a stem 6 having an exterior screw thread for the attachment of a supply pipe or tube, not shown, for the medium under pressure, and the medium under pres- 50 sure is free to flow through a passage 7 in the plug, neck and stem to enter the chamber 8 of the main shell or casing.

A head 9 is located within the chamber 8 of the main shell or casing 1, and has extending forwardly therefrom a tubular neck 10, 55 with a longitudinal passage 11 and termi-

nating at its forward end in a nipple 12, having an exterior screw thread for the attachment of the drill rod or tube. The tubular neck 10 passes through a bearing ring 13 60 held in the shell or casing, which ring is fitted close enough to the side walls of the shell to have the necessary frictional engagement therewith to prevent its turning under the ordinary strain to which it will be subjected, which ring has, in its face, a semi-circular groove or recess 14 forming one-half of a ball race, the other half of which is formed by a semicircular recess 15 in the face of the head 9, so as to furnish a ball 70 race for a plurality of anti-friction balls 16 between the head 9 and the ring 13, so that the head 9 and the tubular neck 10 can revolve freely within the chamber of the main shell or casing. 75

A packing ring 17 of any suitable material encircles the tubular neck 10 in advance of and abutting against the face of the ring 13, and a ring 18 encircles the tubular neck 10 and abuts against the packing ring 17, when 80 the parts are assembled. A ring or tubular plug 19 is entered into the forward end of the main shell or casing, and has an annular flange or rim 20 which, when the parts are together, abuts against the end face of the 85 main shell or casing, as shown in Fig. 1. The tubular plug 19 has an interior screw thread, which threads onto a screw thread around the exterior of the tubular neck 10, connecting the plug and the neck, one with 90 the other. The rear end face of the tubular plug 19 has therein a semi-circular recess 21, forming one-half of a ball race, and the other half of the ball race is formed in the front face of the ring 18 by a semi-circular 95 recess 22, the two recesses 21 and 22 constituting a ball race for receiving a plurality of anti-friction balls 23 by which, in connection with the anti-friction balls 16, the head and the tubular neck, with the tubular 100 plug 19, are free to revolve within the shell or casing 1 of the coupling.

The front face of the flange 20, adjacent to the tubular neck 10, has therein a recess or groove 24, which receives a flat ring 25 having a tooth or lug 26, which enters a groove 27 formed in the threaded portion of the tubular neck, as shown in Fig. 1, the tooth serving as a key to prevent rotative movement of the plug 19 about the neck 10 after 110 the parts have been assembled. A lock or jam nut 28 is threaded onto the threaded

portion of the tubular neck 10, and serves to hold the tubular plug 19 against unscrewing in the operation of the drill. A ring or band 29 encircles the tubular neck 10 in advance of the lock or jam nut 28, and abuts against the shoulder formed by the threaded portion of the tubular neck, as shown in Fig. 1. This ring or band 29 has, on one side, a hole 31 which can be brought into communication with a hole 32 in the tubular neck 10, for permitting oil to flow through the interior passage in the drill shank and oil the hammer and analogous parts operating at the terminus of the shank; and the neck or band 29 is held in place by a set screw 33, the stem of which passes through a slot 34 in the ring or band and enters the wall of the tubular neck, as shown in Fig. 4, so that the ring or band can be turned to open communication between the oil holes 31 and 32, or close communication between such holes, when the holes are not required for oiling purposes. The oil will flow in the same direction as the fluid through the stem; hence, the fluid will assist in carrying the oil to the hammer and other parts, not shown, carried on the end of the stem of the drill rod.

The drill rod, in the construction shown, is a tubular rod having a wall or body 35 and a spiral flange or wing 36, encircling the center or body 35, with a spiral channel or passage 37 between the spiral flange or wing; and the rod has a passage 38, which is in communication with the passage 11 of the coupling neck and head, so that a medium under pressure can be forced through the tubular drill rod for use. It is to be understood that the coupling can be used with a solid drill rod instead of a tubular drill rod.

The parts are assembled by entering the head 9 and the tubular neck 10 into the chamber 8 of the main shell or casing, from the opposite end to that in which the plug 4 is entered and then entering the balls 16 into the half race 15, after which the collar 13 is entered into position to complete the ball race; and the packing ring 17 and ring 18 are then entered into position within the main shell or casing 1 and around the tubular neck 10 of the coupling. The balls 23 are then entered into the half race 22, and the tubular head or gland 19 is threaded onto the tubular neck 10, completing the ball race for the balls 23. The flat ring 25 is entered into the recess 24, with the lip or tooth 26 engaged with the slot 27, after which the lock or jam nut 28 is threaded into place, completing the assembling of the coupling. The oiling ring or band 29 is slipped into place and secured by the screw 33 or otherwise, so as to be free to turn.

In use the drill rod is connected with the tubular neck 10 by screw-threading the two

together, or otherwise, so that the tubular neck, and the parts having a fixed relation therewith, can be revolved to revolve the drill rod. The coupling, if used with a medium under pressure, is effectually packed against the venting of pressure by the packing ring 17 and by the plug or head 3, to the threaded stem of which the tube or pipe for supplying pressure is attached. The packing ring and the race rings do not revolve, but remain stationary, and the anti-friction balls 16 and 23 furnish a ball bearing for the head 9 and tubular neck 10 of the coupling, by which a free revolving of the head and tubular neck is obtained. The coupling, as a whole, enables a tube for supplying a medium under pressure and a drill rod to be connected together in such manner as to effectively prevent venting of the pressure and at the same time permit the drill rod to be revolved; and the oiling band or ring enables the bearing for the tubular neck and its head to be lubricated without the venting of the medium under pressure.

What I claim as new and desire to secure by Letters Patent is:

1. In a drill coupling, the combination of a main casing, a hollow plug, having a passage therethrough, secured into and closing one end of the casing, a tubular neck extending into the casing and adapted to revolve therein, said neck having on one end a head adapted to lie and revolve within said casing, a plug attached to the neck and entered into the other end of the casing, and adapted to revolve within the casing, rings entered between the plug and head and loosely surrounding the sleeve, said rings being held from rotation within the casing by frictional contact with the walls of the casing, roller bearings inserted between one of the rings and the head and between the other ring and the plug, and forming anti-frictional surfaces on which the head and plug travel when the neck is rotated, and a drill shank connected to the other end of the neck, substantially as described.

2. In a drill coupling, the combination of a main casing, a plug secured into and closing one end of the casing, said plug having a passage therethrough for the admission of fluid under pressure to the casing, a tubular neck extending into the casing and adapted to revolve therein, and having on one end a head adapted to lie and revolve within said casing, a plug attached to said neck and entered into the other end of the casing, and adapted to revolve within said casing, and rings interposed between the plug and the head and loosely surrounding the neck, said rings being held from movement within said casing by frictional contact with the walls of the casing and serving to prevent lateral movement of the neck and its parts within the casing, substantially as described.

5

3. In a drill coupling, the combination of a main casing, a hollow plug, having a passage therethrough, secured into and closing one end of the casing, a tubular neck extending into the casing and adapted to revolve therein, said neck having on one end a head adapted to lie and revolve within said casing, a plug attached to the neck and entered into the other end of the casing, and adapted to revolve within the casing, rings entered between the plug and head and loosely surrounding the sleeve, a ring of packing material interposed between said rings, said rings being held from rotation within the casing by frictional contact with the walls of the casing, roller bearings inserted between one of the rings and the head and between the other ring and the plug, and forming anti-frictional surfaces on which the head and plug travel when the neck is rotated, and a drill shank connected to the other end of the neck, substantially as described. 70

5 10 15 20 25 30 35 40 45 50 55 60 65

4. In a drill coupling, the combination of a main casing, a plug secured into and inclosed in one end of the casing, said plug having a passage therethrough for the admission of fluid under pressure to the casing, a tubular neck extending into the casing and adapted to revolve therein, and having on one end a head adapted to lie and revolve within said casing, a plug attached to said neck and entered into the other end of the casing, and adapted to revolve within said casing, a locking ring entered into a recess in the face of the plug, said locking ring being provided with a tooth adapted to enter a groove in the outer face of the neck and preventing loosening of the plug from the neck during the rotation of the neck, and rings interposed between the plug and the head and loosely surrounding the neck, said rings being held from movement within said casing by frictional contact with the walls of the casing and serving to prevent lateral movement of the neck and its parts within the casing, substantially as described. 80 85 90 95 100 105 110 115 120 125 130

5. In a drill coupling, the combination of a main casing, a hollow plug, having a passage therethrough, secured into and closing one end of the casing, a tubular neck extending into the casing and adapted to revolve therein, said neck having on one side a head adapted to lie and revolve within said casing, a plug attached to the neck and entered into the other end of the casing, and adapted to revolve within the casing, a locking ring entered into a recess in the face of the plug, said locking ring being provided with a tooth adapted to enter a groove in the outer face of the neck and preventing loosening of the plug from the neck during the rotation of the neck, rings entered between the plug and the head and loosely surrounding the sleeve, said rings being held from rotation within the casing by frictional contact with the walls of the casing, roller bearings inserted between one of the rings and the head and between the other ring and the plug, and forming anti-frictional surfaces on which the head and plug travel when the neck is rotated, a drill shank connected to the other end of the neck, said neck having a hole therein to permit oil to enter the interior of the neck and flow downward therein, to oil the drilling mechanism attached to the lower end of the drill rod, and means for closing said opening, substantially as described. 110 115 120 125 130

6. In a drill coupling, the combination of a main casing, a plug secured into and inclosed in one end of the casing, said plug having a passage therethrough for the admission of fluid under pressure to the casing, a tubular neck extending into the casing and adapted to revolve therein, and having on one end a head adapted to lie and revolve within said casing, a plug attached 130

to said neck and entered into the other end of the casing, and adapted to revolve within said casing, rings interposed between the plug and the head and loosely surrounding the neck, said rings being held from movement within said casing by frictional contact with the walls of the casing and serving to prevent lateral movement of the neck and its parts within the casing, said neck 10 having a hole therein to permit oil to enter

the interior of the neck and flow downward therein, to oil the drilling mechanism attached to the lower end of the drill rod, and means for closing said opening, substantially as described.
